[57] CLAIM

The ornamental design for a fireplace or similar article, substantially as shown and described.

DESCRIPTION

FIG. 1 is a front isometric view of a fireplace embodying our new design as seen from the top and either the right or left side thereof;

FIG. 2 is a top plan view thereof;

FIG. 3 is a rear elevational view thereof; and

FIG. 4 is a left side elevational view thereof, the right side being a mirror image thereof.

FIG. 1

FIG. 2

FIG. 3

FIG. 4
